Primary Examiner—Stella M Reid*Assistant Examiner*—Elizabeth J Oswecki*(74) Attorney, Agent, or Firm*—Mario A. Tabone(57) **CLAIM**

The ornamental design for a container body portion, as shown and described.

DESCRIPTION

FIG. 1 is a top, front perspective view of a container body portion showing our new design;

FIG. 2 is a front elevational view thereof;

FIG. 3 is a rear elevational view thereof;

FIG. 4 is a top plan view thereof; and,

FIG. 5 is a bottom plan view thereof.

The broken lines shown in the drawing views are for environmental purposes only and form no part of the claimed design.
